US0D1035016S

(12) **United States Design Patent** (10) **Patent No.:** **US D1,035,016 S**
(45) **Date of Patent:** **** Jul. 9, 2024**

(54) **NEUROMUSCULAR ELECTRICAL STIMULATION DEVICE**

(71) Applicant: **Impact IP, LLC**, Rocklin, CA (US)
(72) Inventor: **Ryan Seitz**, Rocklin, CA (US)
(73) Assignee: **Impact IP, LLC**, Rocklin, CA (US)

(**) Term: **15 Years**

(21) Appl. No.: **29/813,073**

(22) Filed: **Oct. 26, 2021**

(51) **LOC (14) Cl.** **24-01**
(52) **U.S. Cl.**

USPC **D24/200**

(57) **CLAIM**

The ornamental design for a neuromuscular electrical stimulation device, as shown and described.

DESCRIPTION

FIG. 1 is an isometric view a neuromuscular electrical stimulation device attached onto a left arm of a human body.

FIG. 2 is a top isometric view thereof.

FIG. 3 is a bottom isometric view thereof.

FIG. 4 is a top view thereof.

FIG. 5 is a bottom view thereof.

FIG. 6 is a front view thereof.

FIG. 7 is a rear view thereof.

FIG. 8 is a left view thereof; and,

FIG. 9 is a right view thereof.

The broken lines showing portions of a human are for the purpose of illustrating environment and form no part of the claim.

1 Claim, 5 Drawing Sheets
